DESIGN FOR A HARNESS-BIT.

Design No. 13,553, dated January 30, 1883.

UNITED STATES PATENT OFFICE

JOHN L. POPE, OF CLEVELAND, OHIO.

DESIGN FOR A HARNESS-BIT.

SPECIFICATION forming part of Design No. 13,553, dated January 30, 1883.
Application filed November 11, 1882. Term of patent 14 years.

To all whom it may concern:

Be it known that I, JOHN L. POPE, of Cleveland, in the county of Cuyahoga and State of Ohio, have invented and produced a new and original Design in Harness-Bits, the following being a specification thereof, reference being had to the accompanying photographs, forming a part thereof.

My invention relates to a novel design for harness-bits; and it consists in certain features of configuration and ornamentation, which will be hereinafter more fully described and claimed.

Two photographs accompany this specification, Figure 1 representing what is known as a "half-cheek" snaffle-bit, and Fig. 2 a "full-cheek" bit.

The same letter of reference I shall use to indicate the same part in the two views.

A is the bit, B B the rein-rings, and C C the cheek-pieces, to which latter my invention particularly relates. The cheek-piece C has two indentations, o o, at its extremity, from which the sides gradually converge and meet the solid neck portion a and ring B near the bit proper. Between the sides of the cheek will be observed handsome ornamentation,

which forms a part of my invention. Near the neck portion is formed an oval figure, n, adjacent to which is a bow or arch, m. Then near the extremity of the cheek there is a quarter-foil, s, in the center of which is a cross.

My novel design, in whole or in part, may be used in any of the known kind of bits.

What I claim as my invention, and desire to secure by Design Letters Patent, is—

1. A harness-bit the cheek-pieces of which have a configuration substantially such as shown and described.

2. A cheek-piece for a harness-bit notched or indented at its extremity, as shown.

3. A cheek-piece for a harness-bit having substantially the configuration and ornamentation shown and described.

4. A cheek-piece for a harness-bit ornamented by a quarterfoil substantially like that shown at s.

In witness whereof I have hereunto set my hand this 3d day of November, 1882.

JOHN L. POPE.

In presence of—

WALTER A. BIDDLE,
GEORGE F. EBERHARD.
